Primary Examiner — Jennifer O King(74) *Attorney, Agent, or Firm* — Bereskin & Parr
LLP/S.E.N.C.R.L, s.r.l.; Isis E. Caulder; Ahmed Elmallah(57) **CLAIM**

The ornamental design for a connector for a light fixture system, as shown and described.

DESCRIPTION

FIG. 1 shows a top perspective view of a connector for a light fixture system of my design;

FIG. 2 shows a bottom perspective view thereof;

FIG. 3 shows a left side elevation view thereof;

FIG. 4 shows a front side elevation view thereof;

FIG. 5 shows a right side elevation view thereof;

FIG. 6 shows a top plan view of the design thereof; and,

FIG. 7 shows a bottom plan view thereof.

The broken line portions are included to show unclaimed subject matter only and form no part of the claimed design.

1 Claim, 3 Drawing Sheets(56)
